[57] CLAIM

The ornamental design for a telephone, as shown and described.

DESCRIPTION

FIG. 1 is a perspective view of a first embodiment of the telephone showing my new design;
FIG. 2 is a perspective view thereof wherein the handset is detached from the base;
FIG. 3 is a top plan view thereof;
FIG. 4 is a left side elevational view thereof;
FIG. 5 is a front elevational view thereof;
FIG. 6 is a bottom plan view thereof;
FIG. 7 is a right side elevational view thereof;
FIG. 8 is a rear elevational view thereof;
FIG. 9 is a top plan view of a second embodiment of the telephone showing my new design;
FIG. 10 is a left side elevational view of the embodiment of FIG. 9;
FIG. 11 is a bottom plan view of the embodiment of FIG. 9;
FIG. 12 is a right side elevational view of the embodiment of FIG. 9; and,
FIG. 13 is a rear elevational view of the embodiment of FIG. 9.
A front elevational view of the embodiment of FIG. 9 is the same as shown in FIG. 5.
